PETER A. LINDBERG, INVENTOR.

BY

Richard D. Oliver
ATTORNEY.

UNITED STATES PATENT OFFICE.

PETER A. LINDBERG, OF MOUNT PLEASANT, UTAH.

RAILROAD MAIL-TRANSFERRING DEVICE.

1,398,136.

Specification of Letters Patent.

Patented Nov. 22, 1921.

Application filed July 8, 1920. Serial No. 394,612.

To all whom it may concern:

Be it known that I, PETER A. LINDBERG, a citizen of the United States, residing at Mount Pleasant, in the county of Sanpete and State of Utah, have invented certain new and useful Improvements in Railroad Mail-Transferring Devices, of which the following is a specification.

This invention has reference to devices for transferring mail to and from rapidly moving trains and has for its principal object the provision of means whereby the transfer of the mail bags from one member to another may be easily and efficiently accomplished without danger of destruction to or loss of the bags.

A further object of the invention resides in the provision of improved and novel means of suspending the bags from the hanger bars so that the exchange of the mail bags can be easily and quickly accomplished without loss of time and without danger of the bags not being properly positioned for the exchange.

With the above and other objects in view the invention resides in the details of construction, combination and arrangement of parts as will be hereinafter more fully pointed out, reference being had to the accompanying drawings, wherein

Figure 1 is a top plan view illustrating the application of the invention.

Fig. 2 is a side elevational view indicating the manner in which the exchange is effected.

Fig. 3 is a sectional, detailed view, taken on the line 3—3 of Fig. 2, the arrows denoting the direction in which the mail car hanger is moving.

Fig. 4 is a side view of the perforated plate or suspension ring of the bag carrier means, and

Fig. 5 is a transverse sectional view taken on the line 5—5 of Fig. 4.

In the drawings, 1 indicates a portion of a car structure in the door way 2 of which is mounted a vertically disposed, movable post 3 having its ends journaled in bearing plates 4 provided on one side of the door way as shown to advantage in Fig. 1. Rigidly connected to post 3 and projecting outwardly therefrom is a hanger arm 5 which carries the oppositely projected hanger bars 6 from which the mail pouch is designed to be hung. When the hanger is not in use, the arm 5 may be swung in an arc through the open door way as indicated by the curved arrow

of Fig. 1 and the door way closed by a sliding door 7, running in a track 8. This door is provided with transversely extending openings 9 located adjacent opposite edges 60 of the door and designed to register with a recess 10 formed in the sides of the car so that the door may be locked in either open or closed position by means of the locking pin 11. This door may be set regardless of 65 whether the car hanger is swung to the inside or outside of the car, the post 3 co-operating with the edge of the door to respectively close the opening. The car hanger is supported and sustained in its outwardly 70 swung position by means of a brace rod 12 hingedly connected to an arm 5 at one end and having a hooked end at the other end for engagement with an eye 13 screwed into the side of the door way as indicated. The receiving station or exchange apparatus 75 designed to co-operate with the mail car in the transferring of the mail pouches from one member to the other comprises a supporting framework 14 resting upon a suitable base or foundation 15 and provided with a projecting bar 16 and pouch hangers 17 somewhat similar to that carried by the mail car.

The pouches to be exchanged are supported from appropriately disposed hanger portions so as to be easily and rapidly exchanged as the train travels past the receiving station. The pouches are suspended from the horizontally disposed hanger bars 6' and 17' respectively by means of flat, disk-like 80 plates 18, preferably stamped from a single sheet of material and of an elongated oval contour grooved or flanged externally about the outer peripheral edge as indicated at 19 to provide a socket for receiving and retaining the looped end 20 by a suitable rope or other connection 21 to the end of which is attached a hook 22. The suspension member is provided adjacent one end with a circular aperture 23 and an elongated opening 95 or slot 24 adjacent the opposite end; the aperture and slot being separated from each other by a bridge piece 25 as shown. At its outermost end the slot is tapered in conformity with the taper of the suspension member as indicated at 26. Each mail pouch has a suspension disk attached thereto by means of the flexible connection 21 which is coiled about the pouch intermediate its end with the hook 22 engaging the rope 21 100 below the perforated end 23. Each bag is then ready to be suspended from its appro-

priate hanger. In arranging the pouch upon the mail car hanger, one of the horizontal hangers, 6', is inserted through the slot 24 engaging the edge 26 thereof so that the pouch will be suspended with the major portion of the slot disposed below the arm 5 and in direct line with an appropriate hanger 17 of the receiving station so that the latter may pass easily into the slot as the mail car moves toward and past it. The tapered formation of the slot 24 permits the suspension ring to oscillate with the motion of the train, and at the same time prevents any sidewise sliding movement of the member on the hanger, thus tending to keep the slot 24 in alinement with the hanger 17 at all times so that there will be no possibility of the suspension member being jostled away from the hanger so as to fail of being picked up by the latter as the train rushes by. The edge 26 is the only point of suspension of the member 18 and the weight of the pouch carried thereby will steady it against undue oscillating motion. The pouch to be delivered to the moving train would be similarly provided with a suspension member of this character but in this instance the hanger 17' upon which the pouch is to be supported is inserted through aperture 23 so that the slot 24 will be positioned above the arm 16 and in alinement with the car hanger 6. The weight of the pouch carried by the rope 21 tends to keep the member 18 in vertically disposed position, aided by the partly solid and naturally heavier lower portion 27 of the suspension ring. It may thus be seen that the arrangement of an aperture and slot adjacent opposite ends of the supporting member adapt it to the alternate use of such ends, in that the slotted end constitutes the point of suspension when hanging the mail pouch of the train, whereas, when the station pouch is hung, the apertured end of the plate is used, the same slipping over the hanger arm. When the plate is supported at the apertured end 23, the slotted end is projected above the support as indicated at the right of Fig. 3. When the plate is suspended from the slotted end, the major portion of the slot depends below the hanger arm. The particular location of the slotted end, with respect to the supporting hanger arm, depends, of course, upon whether the hanger arm which passes into the slot is located above or below the hanger arm upon which the plate is supported. Hence, the ends of the plate are used alternately in locating the slotted portion in line with the plate-engaging hanger arm.

In transferring the mail pouches or bags from one car to the station and vice versa, it will be noted from a consideration of Figs. 1 and 2 that as the mail car hanger passes above the station receiving hanger, the inwardly disposed rods 6 and 17 each enter the slot 24 of one of the bag carriers suspended from the hangers 6' and 17'. The abutment of the end of the respective arms 5 and 16 with the suspension member of the opposite hanger, causes the carriers with hangers 6 and 17 to become disengaged from the supporting hanger 6' and 17' as the train passes the receiving station and to become engaged with hangers 6 and 17 thus effecting an exchange of the pouches without loss of time and without danger of destruction to the bag or its contents. After a station is passed, the door of a mail car may be opened and the brace rod 12 released to permit the hanger to be easily swung into the car and the mail bag removed. Mail bags may also be hung on the hanger while inside the car and the latter then swung out into position when nearing the station, ready to deposit one bag and pick up another. The hangers can be built high enough so as not to interfere with the movement of the mail clerks. In case there should be any danger of the bags blowing off from the rear part of the hanger while the train is approaching the station in a severe wind, it could be held in position by the cord in the hands of the mail clerk until the station hanger is reached.

From the above description, taken in connection with the accompanying drawings it may be seen that the invention herein provided contemplates the provision of means for facilitating exchange of mail bags with a moving train and including novel suspension means for the bags in the form of ring like members provided with a large or upper opening for engagement with the bar hanger and a small or lower opening for engagement with the depot hanger; the bags being suitably connected to each of the said ring like members and hung from their respective supports in the proper position according to the direction the train is moving.

Having thus fully described my invention what I claim as new and desire to secure by Letters Patent is:

1. Suspension means for a mail bag comprising a supporting member having an encircling groove and perforated inwardly of the groove and adjacent each end to permit of alternate use of such ends for purpose of supporting the bag in the transfer of the latter, and flexible tie means accommodated in said groove and providing means for connecting the mail bag to the said member.
2. Suspension means for a mail bag comprising an oval shaped supporting member perforated adjacent each end to permit of alternate use of such ends for purposes of supporting the bag in the transfer of the latter, and grooved about its outer periphery to provide a rope socket, and rope means for connecting the mail bag to said member, said rope being looped about the grooved periphery of the member.

3. Suspension means for a mail bag comprising an externally flanged supporting ring, bridged inwardly of its sides to provide a large opening adjacent one end and a 5 small aperture adjacent the other end, whereby the said member may be alternately supported from either end, a rope connecting the mail bag to said member, a hook on one end of said rope and a loop on the other end 10 for accommodation between the flanges of the said member.

4. A railroad mail transferring device comprising a hanger support having a delivery arm and a catching arm, an elliptical 15 shaped suspension member having a long slot inwardly of one end and a circular opening inwardly of the other end, respectively alining with the longitudinal axis of the

member and adapting either end of the member for engagement with any arm of the 20 hanger whereby the member may be suspended therefrom with the slotted portion disposed above or below the supporting arm, and bag-holding means depending from the end of the member adjacent the circular 25 opening and in line with the longitudinal axis thereof for holding the member balanced in position by the weight of the suspended bag.

In testimony whereof I affix my signature 30 in presence of two witnesses.

PETER A. LINDBERG.
